DESIGN FOR A JEWELRY DISPLAY CASE

Leo Flier, Brooklyn, N. Y.

Application March 14, 1936, Serial No. 61,633

Term of patent 7 years

To all whom it may concern:

Be it known that I, Leo Flier, a citizen of Russia and a resident of the city of New York, Borough of Brooklyn, county of Kings, and State of New York, have invented a new, original, and ornamental Design for a Jewelry Display Case, of which the following is a specification, reference being had to the accompanying drawing, forming part thereof, in which—

Figure 1 is a perspective view of a jewelry display case in opened position, showing my new design;

Figure 2 is a side view of said jewelry display case in opened position;

Figure 3 is a perspective view of said jewelry display case in closed position; and

Figure 4 is a bottom plan view.

I claim:

The ornamental design for a jewelry display case, substantially as shown and described.

LEO FLIER.
